UNITED STATES PATENT OFFICE.

FRANK STACEY, OF BIRMINGHAM, ENGLAND.

GRINDING-MACHINE.

1,400,466.

Specification of Letters Patent. Patented Dec. 13, 1921.

Application filed June 5, 1920. Serial No. 386,813.

To all whom it may concern:

Be it known that I, FRANK STACEY, subject of the King of Great Britain, residing at Vauxhall street, Birmingham, England, 5 flour-milling engineer, have invented certain new and useful Improvements in Grinding-Machines, (for which I have filed application in England Feb. 5, 1919, No. 2794,) of which the following is a specification.

10 The invention provides the hereinafter described and claimed improved grinding machine of the grinding wheel type, particularly adaptable for grinding the peripheries of rolls.

15 The type of machine to which the invention relates is that in which the roll or work to be operated upon is revolvably mounted upon a support which bodily moves for longitudinal movement of said roll or work 20 and in which the grinding wheel except for revolution and advancing movement for cut, is immovable.

According to the present invention, a 25 strongly built bracket carries the grinding wheel or wheels, which bracket crosses the roll or work in a bridge-like manner and has both of its ends or feet strongly fitted to slide-supports whereby said bracket is strongly mounted at said ends or feet and 30 may be moved transversely of the roll or work to effect a grinding cut. Said roll or work is positioned beneath the bridge-like bracket in such disposition in relation to the grinding wheel or wheels that the grinding 35 stresses are oblique and partly borne by the slideways and partly by screw devices used to move the ends or feet in said slideways to effect a grinding cut.

40 A machine suitable for chilled roll grinding is illustrated by the accompanying sheets of drawings, wherein—

Figure 1 is a front elevation.

Fig. 2 is an end elevation, and

Fig. 3 is a plan of the bridge-like bracket 45 separately.

The roll *a* to be ground on its periphery is shown as mounted by its shaft ends *a*² *a*² within bearing brackets *e*, *e* rigidly attached to a saddle *d* arranged for movement upon a 50 bed *e* by a screw *f* and a screw box *g* suitably applied between the bed and the saddle. Rolls to be ground are similarly mounted and traversed in existing wheel grinding machines.

55 A bridge-like bracket *h* supports the

grinding wheel *i* between the ends *h*², *h*², of said bracket, which ends are movably anchored to the upper ends of opposite uprights *l*² and *m*² of front and rear extensions *l* and *m* of the bed *e*. Within the space 60 between these uprights the saddle *d* carrying the roll *a* is mounted to move. The bridge-like bracket *h* is movably anchored forwardly and rearwardly of the grinding wheel on each side the roll mounting, so that 65 spring in the bridge-like bracket is prevented, said bracket being strongly built and also strongly but movably mounted on the standards. In the present instance such movable mounting is shown as consisting of 70 *V* slideways *l*³ *m*³ formed on standards engaging similarly-shaped grooves in the feet of the bracket. The ends or feet *h*², *h*², are moved in the slideways to put the grinding wheel on the roll by a screw *n* carried 75 by one of the standards and engaging a screw box, *n*², carried by one of said feet. The bridge-like bracket *h* comprises two members *h*⁴, *h*⁵ extending longitudinally 80 of the bridge a distance apart and rigidly connected at their ends so that the grinding wheel *i* revolves in a space *h*⁶ between said two members which are additionally stayed to each other transversely by integral transverse webs such as *h*⁷ and *h*⁸. The bearings 85 for the grinding wheel *i* are provided on the two members *h*⁴ and *h*⁵ at *h*⁹ and *h*¹⁰ respectively.

It will be clear from the drawings that the roll or work *a* is mounted and moved under 90 the bridge, and that the grinding wheel is supported on the bridge, and that the latter, which is strongly built and also strongly but movably mounted at its ends to the bed most efficiently holds the grinding wheel up to its 95 work without springing movement, the grinding stresses between the roll and the wheel being oblique and partly borne by the slideways *l*³, *m*³ and by the screw devices *n*, *n*².

The grinding wheel is shown as driven from the pulleys *o*, *o*² by twin belts. *r* indicates a pulley or wheel for slowly revolving the roll *a*. The screw *f* is mounted in bearings *f*², *f*³ in the bed *e* and is revolved from 105 the pulleys *x*.

Having now described my invention what I claim and desire to secure by Letters Patent is:—

1. In a grinding machine, the combination 110

of a support movable on a bed for the longitudinal movement of the roll or work, means for revolving the roll or work upon the support, a bracket spanning the work and 5 adapted to carry the grinding wheel, said bracket being slidably fitted to supports on said bed, means for moving the bracket in its supports for grinding cut, and means for revolving the grinding wheel, substantially 10 as described.

2. In a grinding machine, the combination of a support movable on a bed for the longitudinal movement of the roll or work, means for revolving the roll or work upon the support, a bracket spanning the work and 15 adapted to carry the grinding wheel, said bracket being slidably fitted to supports on said bed, means for moving the bracket in its supports for grinding cut so that the 20 grinding stresses are oblique and partly borne by the slideways and by said means,

and means for revolving the grinding wheel, substantially as described.

3. In a grinding machine, the combination of a bed, a work-carrying support movable 25 on said bed, screw devices for moving said support on said bed, means for revolving the roll or work upon the support, a bracket spanning the work and adapted to carry the grinding wheel, said bracket being slidably 30 fitted to supports on said bed, means for moving the bracket in its supports for grinding cut, and means for revolving the grinding wheel, substantially as described.

In testimony whereof I have hereunto set 35 my hand in presence of two subscribing witnesses.

FRANK STACEY.
